By *Hannia Goldsborough O'Neill Atty.*

UNITED STATES PATENT OFFICE.

JAMES FRANCIS BERRY, JR., OF HONOLULU, TERRITORY OF HAWAII, ASSIGNOR TO
HONOLULU IRON WORKS COMPANY, OF HONOLULU, TERRITORY OF HAWAII, A
CORPORATION OF HAWAII.

INTERMEDIATE CONVEYER.

1,191,059.

Specification of Letters Patent.

Patented July 11, 1916.

Application filed August 24, 1914, Serial No. 858,225. Renewed June 6, 1916. Serial No. 102,088.

To all whom it may concern:

Be it known that I, JAMES FRANCIS BERRY, Jr., a citizen of the United States, residing at Honolulu, in the county of Honolulu, Territory of Hawaii, have invented certain new and useful Improvements in Intermediate Conveyers; and I do hereby declare the following to be a full, clear, and exact description of the invention, such as will enable others skilled in the art to which it appertains to make and use the same.

This invention relates to sugar cane mills and particularly to intermediate conveyers used between such mills to convey the crushed cane or bagasse discharged from one mill and feed it to the succeeding mill.

Intermediate conveyers usually have an endless belt or apron upon which this material is carried, or they employ chains with fingers or flights attached thereto to engage and drag this material. Belts are objectionable on account of their stretching and bagging, and aprons of steel slats secured to link belts give trouble due to the breakage of the chains and the slats.

The present invention contemplates, a fourth roller hinged to the housings above and coöperating with the discharge roller, this fourth roller provided with circumferential grooves, a plurality of endless chains or belts running in said grooves and driven by a shaft forward of the mill to be fed, and plates attached to said chains or belts adapted to engage the top of the blanket of bagasse discharged from between the fourth and discharge rollers and aid the movement of the same in the trough connecting the mills, as will hereinafter more fully appear.

The invention consists in the combination and arrangement of parts as hereinafter described and claimed, reference being had to the accompanying drawings, forming a part of this specification, in which—

Figure 1 represents in side elevation an intermediate conveyer between two sugar cane mills embodying my invention. Fig. 2 is a view of a portion of the fourth roller showing the circumferential grooves. Fig. 3 is a sectional detail on a larger scale showing the chain in one of these grooves.

Referring to the drawings, 5 represents the trough of the intermediate conveyer con-

necting the three roller sugar cane mills A and B. The roller 6 is journaled in the boxes 7 attached to the levers 8 which are hinged to the brackets 9 secured to the housings of the mill A. The roller 6 is thus revoluble rearward of the top roller and above the discharge roller of the mill A and co-operates with the latter roller. The shaft 10 is journaled at the upper end of the trough 5 in the bracket bearings 11 secured to the housings of mill B. The shaft 10 is revolved from the top roller of mill B by means of the sprockets 12 and 13 connected by the chain 14. A plurality of endless link belts 15 pass around the sprockets 16 on the shaft 10 and the roller 6 in the circumferential grooves 6^a, the function of the latter being to permit the belts 15 to clear the discharge roller of mill A. Plates 17 are attached to the links 15 to engage the top of the blanket of the crushed cane or bagasse discharged from between the roller 6 and the discharge roller of mill A. To prevent the possibility of the grooves 6^a becoming clogged by trash or bagasse, scraper bars 18 may be employed.

In operation, the crushed cane discharged from mill A passes under the fourth roller 6 and is discharged into the lower end of the trough 5 and continues to move up the trough by the assistance of the plates 17 attached to the chains 15 which move in the same direction and engage the top of the blanket of bagasse. The weight of the roller 6 compresses or flattens out the bagasse discharged from the mill A, the roller 6 swinging on its hinges toward or away from the discharge roller of mill A depending upon the thickness of the blanket passing under the roller 6. Arriving at the upper end of the trough 5 the bagasse is fed to the mill B in the usual manner.

It will be understood that the term chains as used in the above description and in the claims is intended to cover any kind of suitable conveyer belts capable of coöperating with the fourth rollers and the remaining structure in the same manner that the link chains above described coöperate with the remaining structure.

If desired, maceration may be applied in any well known manner.

I claim:

1. An intermediate conveyer comprising, a

trough connecting two mills, a fourth roller revolvable in bearings hinged to the housings and coöperating with the discharge roller of the first mill, circumferential grooves in said 5 fourth roller, a shaft at the rear end of said trough revolved by the second mill, endless chains running in said grooves and driven by said shaft, and plates attached to said chains adapted to engage the top of the 10 blanket of bagasse and aid its movement in said trough, substantially as described.

2. In an intermediate conveyer, a fourth roller provided with circumferential grooves, 15 belts in said grooves having plates attached, and means for keeping said grooves free of trash or bagasse, substantially as described.

3. The combination with two sugar cane 20 mills, of an intermediate conveyer therefor comprising a fourth roller secured to the housing of each mill, one of said rollers having its surface in close proximity with the discharge roller of the corresponding mill, said roller also having a plurality of

circumferential grooves, conveyer chains passing over said fourth rollers, each of the 25 conveyer chains running in one of said grooves, and a plurality of conveyer plates attached to said chains.

4. The combination with two sugar cane mills, of a fourth roller associated with each 30 of the mills, one of said fourth rollers being hingedly mounted on the mill and having its surface lying in close proximity with the surface of one of the rollers of the mill, said hingedly mounted roller having a plurality of circumferential grooves, a plurality of conveyer chains passing over said fourth rollers, each of said chains running in one 35 of said grooves, and a plurality of conveyer plates attached to said chains.

In testimony whereof I affix my signature, in presence of two witnesses.

JAMES FRANCIS BERRY, JR.
